LIFTING JACK ADAPTER DEVICE

Clarence Henry Madden, Hollis, Okla.

Application June 24, 1944, Serial No. 541,897

3 Claims. (Cl. 254—133)

This invention relates to a novel and improved adapter device for use in connection with a conventional vehicle lifting jack, and has more specific reference to a type which embodies an elongated horizontally disposable reach bar constructed at one end for attachment to the vehicle and at its opposite end to rest upon the jack, whereby to provide a satisfactory and convenient means of transmitting, by remote control, the lifting forces of the jack to the vehicle being lifted.

Admittedly, lifting jack adapters of this general type are well known in the art to which the invention appertains. Therefore, such novelty as is herein presented is predicated upon the specific features of refinement and explicit details which contribute in the production of a specifically distinct and improved adapter.

In carrying out the principles of the invention, I have found it expedient and practicable to utilize a simple reach bar, this having, at its inner end, means to embrace the leaf spring and an adjustable chock forming a fulcrum, said parts being expressly designed for expedient coaction and to satisfactorily retain the adapter in dependable position for adequate use.

Other features and advantages will become more readily apparent from the following description and the accompanying illustrative drawings.

In the drawings, wherein like numerals are employed to designate like parts throughout the same—

Figure 1 is a side elevational view of a lifting jack adapter device constructed in accordance with the principles of this invention showing the preferred manner in which it is used.

Figure 2 is a vertical section on the plane of the line 2—2 of Figure 1.

Figure 3 is a perspective view of the adapter per se.

Figure 4 is an inner or front end elevation thereof, this disclosing the hook-like spring-engaging cleat.

Figure 5 is a side elevational view of a fragmentary type based on Figure 4.

Figure 6 is a side elevational view of the reach bar.

Figure 7 is an end elevation of the bar observing Figure 6 in a direction from left to right.

Figures 8 and 9 are detail views of the shiftable fulcrum forming chock.

Reference being had to the complete assemblage seen in Figure 3, it will be observed that the adapter comprises an elongated reach bar 10 preferably of rectangular cross-sectional form.

As brought out better in Figure 6, this is provided with a front axle-engaging notch 11 at one end and with a keying lug 12 at the opposite end. The upper edge portion is provided on opposite sides with channels or grooves forming duplicate keyways 13. These keyways serve to accommodate keying ribs formed in the basal portion 14 of the wedge or chock 15. This part 15 is of block-like design and includes an inclined body portion 16 which forms the wedge proper. The part 14 is slipped over the end of the bar, with the ribs in the keyways 13, this as brought out in Figure 3.

The substantially C-shaped cleat 17 has a slot 18 fitting over the keying lug 12 and clamped in place by a suitable fastener 19.

In Figures 1 and 2, the rear axle of the vehicle is indicated at A and the leaf spring at B. The conventional lifting jack is denoted at C.

20 The adapter device in use is shown in Figure 1. As here observed the accommodation or keeper notch in the cleat 17 embraces the spring B. The chock or wedge 15 is interposed between the reach bar and the overlying leaves of the spring. It is shoved tightly between these parts so as to provide the desired clamping and fulcruming action. The rear end of the reach bar extends to a point sufficiently clear of the fenders and chassis to permit the lifting jack to be placed therebeneath as brought out in Figure 1. Consequently, the reach bar serves as a cantilever and transmits the lifting forces of the jack to the axle region of the spring B. Thus, by remote control the jack elevates the spring, axle and wheels and, in turn, the vehicle, in an obvious manner.

As before explained, this device is primarily intended for use on the rear of the vehicle where it is exceedingly difficult to place a jack beneath the axle region of the spring. However, the 40 structure is convertible in the sense that the notch 11 can be used for "hooking" the face flange on the front axle (not shown) if and when desired. Consequently, the adapter is of a convertible character.

45 It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A lifting jack adapter of the class described comprising an elongated reach and lifting force applicator bar having a detachable spring engaging cleat at one end and a longitudinally shiftable fulcrumming chock on its intermediate portion.

2. A lifting jack adapter device of the class described comprising an elongated reach bar having longitudinal grooves in opposite sides forming keyways, a chock including a wedge and a body portion, said body portion having keying ribs, said ribs being slideable in said keyways, and

means on one end of said bar closing said keyways and adapted to engage a leaf spring.

3. A lifting jack adapter device of the class described comprising an elongated reach bar having longitudinal grooves in opposite sides forming keyways, a chock including a wedge and a body portion, said body portion having keying ribs, said ribs being slideable in said keyways, and means on one end of said bar closing said keyways and adapted to engage a leaf spring, said means comprising a detachable C-shaped cleat.

CLARENCE HENRY MADDEN.
